FEED MECHANISM FOR FUELING SYSTEMS

Durbin Van Law, Denver, Colo., assignor, by mesne assignments, to Powderco Inc., Denver, Colo., a corporation of Colorado

Application July 5, 1932, Serial No. 620,872

8 Claims. (Cl. 198—57)

This invention relates to feed-mechanism in mechanical fueling apparatus for furnaces and the like, its main object being to provide a simple and efficient means for evenly removing finely divided coal from a supply-bin and feeding it to a fan or other element by which it is conveyed to the fire-chamber of the furnace. Other objects are to be found in details of construction and in a novel arrangement and combination of parts as will be fully set forth in the following description.

In the accompanying drawing, in which like reference numerals designate corresponding parts throughout the views, Figure 1 represents a partially broken plan-view of an embodiment of the invention, Figure 2 a sectional side-elevation of the same, Figure 3 an enlarged section along the line 3—3 of Figure 1, Figure 4 an enlarged section on the line 4—4 of Figure 2, Figure 5, a section on the line 5—5, Figure 3, and Figure 6 a section along the line 6—6, Figure 3.

A supply bin 5 having feed-holes 6 in its cover plate, has inwardly slanting sides for the supply of coal to a feed-element in accordance with the present invention.

This feed-element comprises an endless chain slanting upwardly in the bottom portion of the bin and supported by sprocket wheels 8 and 9.

The sprocket wheels are enclosed in housings 10 and 12 outside the bin. The housing 10 rotatably supports the sprocket wheel 8 at the upper or discharge-end of the conveyor and has an opening 13 to pass the coal delivered by the conveyor, to the combustion chamber of a furnace or the like by means of a fan or other suitable device. The housing 10 also has a door-closed opening 14 to afford access to the chain. The sprocket wheel 9 at the lower end of the conveyor is mounted for rotation inside its housing 12, by means of a shaft 15, and this shaft connects through the intermediary of a reduction gearing 16 with a conveniently placed motor 17. The upper and lower stretches of the chain move through tubular casings 18 and 19 inside the bin. These casings are at their ends mounted on the front and rear sides of the bin, in register with openings in said sides, and the lower casing has in its upper portion a feed-opening 20 through which coal in the bin, falls upon the chain to be conveyed upwardly to the point of delivery in the housing.

Outside the bin, the casings are continued by tubular sections 21 connecting with the housing

are screwed into a head 22 on the front-side of the bin and by forming the sections with left and right hand screw-threads respectively, the casing may be used as a medium to tension the chain and maintain it in a taut condition.

It will be apparent that in the use of the invention, the lower stretch of the chain only functions as a conveying medium. The coal in the bin passes into a portion of the chain through the feed-opening 20 in the lower-casing 19, and with the exception of this portion, the chain is entirely protected against contact of the coal within the bin.

Wear of the chain is thus reduced to the minimum and a uniform feed of coal to the point of delivery is assured. The load of the chain is discharged immediately after it reaches the housing and the amount carried over the sprocket onto the upper stretch of the chain is negligible.

While the above described invention is particularly adapted for use in association with mechanical fueling apparatus, it will be apparent that the feed-mechanism may be effectively employed for the conveyance of materials other than finely divided coal, within the scope of the invention as defined in the hereunto appended claims.

What I claim and desire to secure by Letters Patent is:

1. Feed mechanism of the character described comprising a bin and, in the lower portion thereof, an endless conveyor, rotary wheels supporting the conveyor outside the bin, a support for one of the wheels, casings inside the bin, enclosing upper and lower stretches of the conveyor, one of the casings having an opening for the passage of contents of the bin, onto the conveyor, and casings for the conveyor outside the bin, supporting one of the supports, said outer casings being mounted for longitudinal adjustment, whereby to vary the distance of the support from the bin.

2. Feed mechanism of the character described comprising a bin and, in the lower portion thereof, an endless conveyor, rotary wheels supporting the conveyor outside the bin, a movable support for one of the wheels, casings inside the bin, enclosing upper and lower stretches of the conveyor, one of the casings having an opening for the passage of contents of the bin, onto the conveyor, and casings for the conveyor outside the bin, in screw-thread connection with the bin and with the movable support, whereby the position of the support relative to the bin, may be adjusted by rotation of the casings.

3. Feed mechanism of the character described

comprising a bin and, in the lower portion thereof, an endless conveyor, rotary wheels supporting the conveyor outside the bin, a movable support for one of the wheels, and casings for the conveyor outside the bin, supporting the support, said casings being mounted for longitudinal adjustment, whereby to vary the distance of the support from the bin.

4. Feed mechanism of the character described comprising a bin and, in the lower portion thereof, an endless conveyor, rotary wheels supporting the conveyor outside the bin, a support for one of the wheels, and casings for the conveyor outside the bin, in screw-thread connection with the bin and with the support, whereby the position of the support relative to the bin, may be adjusted by rotation of the casings.

5. Feed mechanism of the character described comprising a bin and in the lower portion thereof, an endless conveyor, rotary wheels supporting the conveyor outside the bin, a support for one of the wheels, and casings for the conveyor outside the bin, having right and lefthand screw-threaded connections respectively with the support and with the bin, whereby to vary the distance of the support from the bin by rotation of the casings.

6. Feed mechanism of the character described comprising a bin and, in the lower portion thereof, an endless conveyor, rotary wheels supporting the conveyor outside the bin, a support for one of the wheels, and casings for the conveyor outside the bin, having right and lefthand screw-threaded connections respectively with the support and with the bin, whereby to vary the distance of the support from the bin by rotation of the casings.

7. Feed mechanism of the character described comprising a bin and, in the lower portion thereof,

6. Feed mechanism of the character described comprising a bin, heads in opposite sides of the bin having openings for the passage of a conveyor, upper and lower tubes having their ends in said openings, the lower tube having an entrance in its upper side for the admission of material from the bin, and a conveyor in said tubes, passing outside the bin through the openings.

7. Feed mechanism of the character described comprising a bin, heads in opposite sides of the bin having openings for the passage of a conveyor, upper and lower tubes having their ends in said openings, the lower tube having an entrance in its upper side for the admission of material from the bin, a conveyor in said tubes, passing outside the bin through the openings, and closures for the conveyor outside the bin.

8. Feed mechanism of the character described comprising a bin, heads in opposite sides of the bin having openings for the passage of a conveyor, upper and lower tubes having their ends in said openings, the lower tube having an entrance in its upper side for the admission of material from the bin, the walls of the bin converging to said entrance, and a conveyor in said tubes, passing outside the bin through the openings.

DURBIN VAN LAW.
